US0D1054527S

(12) **United States Design Patent** (10) **Patent No.:** **US D1,054,527 S**
(45) **Date of Patent:** **** Dec. 17, 2024**

(54) **FLAME ARRESTOR**

(71) Applicant: **Mark W Wyne**, Wildwood, MO (US)

(72) Inventor: **Mark W Wyne**, Wildwood, MO (US)

(**) Term: **15 Years**

(21) Appl. No.: **29/793,267**

(22) Filed: **Feb. 12, 2022**

(51) LOC (14) Cl. **23-01**

(52) U.S. Cl.

USPC **D23/209**

Primary Examiner — Keli L Hill

(57) **CLAIM**

The ornamental design for a flame arrestor as shown and described.

DESCRIPTION

FIG. 1 is an isometric view of the flame arrestor of this invention;

FIG. 2 is an inverted isometric view of the flame arrestor of this invention;

FIG. 3 is a front view, the back, right, and left side view being a mirror image thereof;

FIG. 4 is a top view; and,

FIG. 5 is a bottom view.

1 Claim, 1 Drawing Sheet
